(57) **CLAIM**

The ornamental design for a cleaning robot as shown and described.

DESCRIPTION

FIG. 1 is a first perspective view of a cleaning robot showing the claimed design in accordance with the present disclosure;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of an encircle portion 9 in FIG. 1;

FIG. 10 is an enlarged view of an encircle portion 10 in FIG. 1; and,

FIG. 11 is an enlarged view of an encircle portion 11 in FIG. 3.

The dash broken lines in the Figures are for the purpose of illustrating portions of the cleaning robot and form no part of the claimed design.

The dot-dash-broken lines in the Figures indicate cutoff boundaries for the enlarged detailed portion views and form no part thereof.

1 Claim, 11 Drawing Sheets
